CLAIM

The ornamental design for a package for data medium, as shown and described.

DESCRIPTION

FIG. 1 is a front view of the package for data medium showing our new design;

FIG. 2 is a side view thereof;

FIG. 3 is a rear view thereof;

FIG. 4 is a bottom view thereof; and,

FIG. 5 is a front perspective view thereof.

The features shown in broken lines depict portions of the package for data medium that form no part of the claimed design.
